UNITED STATES PATENT OFFICE.

ALVARO S. KROTZ, OF DEFIANCE, ASSIGNOR TO HALBERT K. HITCHCOCK,
EDWARD B. MILLER, AND BERTRAM G. WORK, ALL OF AKRON, OHIO.

OIL-FILTER.

SPECIFICATION forming part of Letters Patent No. 448,152, dated March 10, 1891.

Application filed August 21, 1890. Serial No. 362,578. (No model.)

To all whom it may concern.

Be it known that I, ALVARO S. KROTZ, a citizen of the United States, residing at Defiance, in the county of Defiance and State of Ohio, have invented a certain new and useful Improvement in Oil-Filters, of which the following is a specification.

My invention has relation to improvements in filters for cleansing and purifying lubricating-oils that have become charged with foreign substances, as by being used on journal-bearings, screw-cutting machinery, and for like general purposes; and it has for its object the production of a compact, simple, and effective mechanism which shall accomplish the desired end by successively removing the different grades of foreign matter, washing the oil, and delivering it in a purified state.

To the above object my invention consists in the peculiar and novel construction and combination of parts hereinafter described, and then specifically pointed out in the claims, reference being had to the accompanying drawing, forming a part of this specification.

In the accompanying drawing, which is a vertical central section of my improved oil-filter, A is a cylindrical can, of sheet metal, open at the top and closed at the bottom, resting on a suitable base B, and provided with three cocks C C' C'', arranged at different distances from the bottom. Resting on brackets B or other suitable supports within the case A is a horizontal disk E, of sheet metal, having a central orifice to receive a pipe, hereinafter described, and perforated outside of said central orifice with a number of small holes. On this disk is a layer F of filtering material, as cotton waste or sponge, and on this rests a disk G, which serves to compress and retain the material F and by which it is supported. This disk G has a central orifice similar to the central orifice of the disk E and for the same purpose, concentrically about which is a cylinder H, of sheet metal, open at the top, having a water-tight connection with the disk G, inside of which cylinder the disk is solid and outside of it perforated with small holes similar to those in the disk E.

Closely fitted in the central orifices in the disks G E is a vertical pipe or tube I, which

projects a short distance above the former and extends nearly to the bottom of the case A, where it terminates in an inverted flattened conical flange J, having about one-half the diameter of the case A. Supported above and inclosing the upper end of the pipe I is a cap K, whose lower edge is lower than the top of the pipe.

Fitting inside the cylinder H is a smaller cylinder L, open at the top and having a perforated bottom, and provided with a handle M or other suitable device by which it can be raised from the cylinder H, and in which is placed a mass N of filtering material similar to the layer F.

Resting on the top of the case A is a funnel-shaped top O, the lower end of which enters the cylinder H, and across the top of which is a screen composed of parallel bars P. (Shown in cross-section.) Near the bottom of the case A above the flange J is an inwardly-projecting flange Q, of inverted-frusto-conical form.

In operation the case A is filled with water to the line of the cock C'. The oil charged with impurities is cast into the top O, where the coarser parts are arrested by the bars P, and passes into the cylinder H through the filtering material N, which retains finer particles that pass the screen P. In the cylinder H the oil is comparatively stagnant, and heavy particles of foreign matter that were too fine to be arrested by the material N will gravitate to the bottom, while the oil freed therefrom passes down the tube I, and from its lower end spreads itself in minute globules over the under face of the flange J, which, by their buoyancy, roll along said flange until they escape from its outer edge and ascend through the water toward the upper part of the case A. By thus passing through the water the oil is washed of impurities that have escaped the screen N and have not been precipitated and rises through the filtering material F, which arrests any remaining foreign substances and is drawn off in a purified state through the cock C. Impurities lighter than water and heavier than oil will accumulate on top of the water and are removed through the cock C', and heavier articles washed from

the oil are precipitated to the bottom of the case A and drawn off through the cock C''. The flange Q is encountered by the oil globules as they ascend from the outer edge of the flange J, and deflecting them from their direct course causes them to be further washed.

I do not intend by the drawing and specification to confine my invention to the exact proportions shown and described; nor do I limit it to the combination of all the parts, as some of them may be omitted—as, for instance, the flange Q, the cylinder L, and the top O—and still have an operative machine; but

15 What I claim, and desire to secure by Letters Patent, is—

1. The combination, with the inclosing case A, having cocks C C' C'' projecting therefrom at different heights, filtering material F, compressed between perforated plates E G and located substantially centrally in case A, with the cylinder H resting on said plate G, and a pipe I, placed centrally in the plates E G, having a flange J projecting from its lower end, 25 of a cap K, arranged to inclose the upper end of said pipe I, substantially as shown and described.

2. In an oil-filter, the combination of an inclosing case A and perforated plates E G, having located centrally therein a pipe I, with 30 flange J attached to its lower end, of the annular flange Q, attached to the interior of said case A above said flange J and arranged to receive oil escaping over the outer edge of the flange J, substantially as shown and described, 35 and for the purpose specified.

3. The herein-described oil-filter, consisting of the case A, cocks C C' C'', perforated disks E G to retain filtering material F, cylinder H, pipe I, having flange J and cap K, 40 inner cylinder L to receive filtering material N and having a perforated bottom, and top O, provided with parallel bars P, all constructed and arranged substantially as shown and described, and for the purpose specified. 45

In testimony that I claim the above I hereunto set my hand.

ALVARO S. KROTZ.

In presence of—

N. G. JOHNSTON,
K. V. HAYMAKER.
